UNITED STATES PATENT OFFICE

172,989

SIGNAL LIGHT

Grant V. W. Roth, Chicago, Ill.

Application November 9, 1953, Serial No. 27,489

Term of patent 14 years

(Cl. D72—1)

To all whom it may concern:

Be it known that I, Grant V. W. Roth, a citizen of the United States of America, residing at Chicago, in the county of Cook and State of Illinois, have invented a new, original, and ornamental Design for Signal Light, of which the following is a specification, reference being had to the accompanying drawing, forming part thereof.

In the drawing:

Figure 1 is a perspective view of a signal light, showing my new design; and

Figure 2 is a top plan view of the same.

I claim:

The ornamental design for a signal light, as shown.
